(57) **CLAIM**

The ornamental design for a ring with cup mount, as shown and described.

DESCRIPTION

FIG. 1 is a front and bottom perspective view of a ring with cup mount, in accordance with the invention;

FIG. 2 is a right side elevational view thereof, the left side elevational view being a mirror image thereof;

FIG. 3 is a top plan view thereof;

FIG. 4 is a front elevational view thereof, the rear elevational view being the mirror image thereof; and,

FIG. 5 is a bottom plan view thereof.
